UNITED STATES PATENT OFFICE.

LEWIS S. BIXLER, OF KENTON, OHIO, ASSIGNOR TO HARDWARE & WOODENWARE MANUFACTURING COMPANY, OF NEW YORK, N. Y., A CORPORATION OF NEW YORK.

DESIGN FOR A TOY BANK OR SIMILAR ARTICLE.

41,948.

Specification for Design.

Patented Nov. 28, 1911.

Application filed May 1, 1911. Serial No. 624,455. Term of patent 7 years.

To all whom it may concern:

Be it known that I, LEWIS S. BIXLER, a citizen of the United States, residing at Kenton, in the county of Hardin, State of Ohio, have invented a new, original, and ornamental Design for Toy Banks or Similar Articles, of which the following is a specification, reference being had to the accompanying drawing, forming part thereof.

Figure 1 is a top plan view of a bank or

safe embodying my new design; and Fig. 2 is a perspective view.

I claim:

The ornamental design for a toy bank or similar article, as shown.

LEWIS S. BIXLER.

Witnesses:

G. C. FERGUSON,
S. J. HERRING.
